BRUSH HOLDER MOUNTING

John E. Pastoret and John W. Morrow, Pittsburgh, Pa., assignors to Westinghouse Electric Corporation, East Pittsburgh, Pa., a corporation of Pennsylvania

Application April 19, 1947, Serial No. 742,558

4 Claims. (Cl. 171—323)

1

Our invention relates to an improved form of brushholder-mounting, for supporting the brush-holders of a dynamo-electric machine. While our invention has desirable features of general utility, it was more particularly designed for an explosion-resistant motor, for use on mine-locomotives. On these explosion-resistant motors, the specifications of the United States Bureau of Mines require a minimum number of holes through the motor-frame, with special limitations regarding the non-removability of the bolts or studs which pass through those holes. Previous attempts to meet such specifications have resulted in extremely awkward brushholder-mountings, which were very inconvenient to the customer, in his efforts to adjust or service the brushholders from time to time, and quite costly to the manufacturer, in assembling the mounting, and also somewhat deficient in regard to the degree of accuracy which was obtainable in the course of manufacture.

The object of our present invention is to provide a novel form of brushholder-mounting, such as is hereinafter described and claimed, and illustrated in the drawing, wherein

Figure 1 is a longitudinal sectional view of the top half of one end of a mine-locomotive motor, embodying our invention in an illustrative form of embodiment:

Fig. 2 is a sectional view through the end-wall of the motor-frame, on the section-line II—II of Fig. 1, showing a plan view of the brushholder-mounting; and

Fig. 3 is an end view of the inner support-block of the brushholder-mounting, as seen from the inside of the machine.

We have illustrated our invention as being applied to a direct-current traction-motor, designed for use on a mine-locomotive. The motor has a stator-frame 1, having an end-wall 2 at the commutator-end of the machine. The end-wall 2 carries a bearing 3 for the shaft 4 of the rotor-member 5, which has a commutator 6 at the illustrated end of the machine. The rotor-member 4 rotates within a stator-member 7 which is carried by the stator-frame 1.

An important feature of our invention is that we utilize a brushholder-mounting of such nature that it is possible for us to provide the inner surface of the end-wall 2 of the stator-frame with a flat, accurately machined, brushholder-supporting surface 18, which can be very accurately and very economically provided by a boring-operation, so as to provide a finished surface, extending around the end-wall at right angles to

2
the motor-shaft. The end-wall 2 of the stator-frame has a plurality of axially extending holes 11 therein, which pass through this machined surface 10 at various points around the frame, each hole corresponding to one brushholder-mounting.

In our invention, it is possible, and therefore desirable, to utilize underhung brushholders 12, as distinguished from overhung brushholders. An 10 underhung brushholder is characterized by two support-pins 13 which extend radially inwardly from an outer corner of the brushholder-frame, so that the brushholder is supported, from the lower ends of these pins, at a support-point which 15 is close to the point where the brushes 14 bear on the commutator 6, thus providing a very desirable brushholder-mounting, which is not only inherently rigid, but which requires a minimum of overhead or radial space.

of overhead of radial space.

20 In the illustrated form of embodiment of our brushholder-mounting, the mounting for each brushholder comprises a pair of outer and inner support-blocks 15 and 16 respectively, using the terms "outer" and "inner" as referring to the 25 axial direction, the inner block being toward the inside of the machine, and the outer block being toward the end-wall 2. These outer and inner support-blocks 15 and 16 have two sets of approximately semi-cylindrical seats 17 for clamp- 30 ingly embracing the support-pins 13 of the associated brushholder.

The outer support-block 15 has a flat surface in engagement with the flat machine surface 10 of the motor-frame, and it has a hole 18, between 35 its two pin-engaging seats 17, said hole acting as a continuation of the corresponding axially extending hole 11 in the motor-frame. In carrying out our invention, it is an easy manufacturing-procedure to make the outer support-block 15 have a predetermined thickness which accurately 40 spaces the two brushholder-pins 13 from the accurately machined surface 19 of the motor-frame. In the process of assembling the brushholder-mountings, these outer support-blocks 15 are first 45 located in seating-engagement with the machined surface 10, with the holes 18 of the blocks registering with the corresponding holes 11 in the motor-frame, and with the several pin-receiving seats 17 disposed in the desired radial direction, 50 and then each of these outer blocks 15 is permanently secured in place, against the end-wall 2 of the motor-frame, which may be done by means of a line of welding 19 around each of the outer blocks 15.

55 In accordance with our invention, each of the outer blocks 15.

inner blocks 16 carries a stud 21 which extends through the corresponding holes 18 and 11 in the associated outer support-block 15 and in the motor-frame 1, with a flame-sealing explosion-resistant clearance within said holes. The stud 21 of each of the brushholder-mountings has a nut 22 threaded on it, to engage the outer surface of the motor-frame, and it also has a head 24, or other means, on its outer end, for preventing the accidental removal of said nut 22 after it has been turned back sufficiently to loosen the clamping-engagement of the associated inner block 16 against the corresponding support-pins 13. In an explosion-resistant motor, designed to meet Bureau of Mines specifications, the nut-trapping head 24 is permanently and irremovably secured to the outer end of the stud 21, as by being integrally formed therewith, or welded thereto, thus permanently preventing the complete removal of the nut 22.

As shown more clearly in Fig. 3, the stud 21 is rigidly or fixedly secured to its inner support-block 16, but it is preferably removably secured thereto, in the sense that it can be removed only after the motor has been opened up, and after a setscrew 26 has been removed from an edge of the inner end of the stud 21. According to this construction, the inner end of the stud 21 is screwed into a threaded hole 27 in the inner block 16, and then the stud is locked in place by means of the setscrew 26.

In the use of our improved brushholder-mounting, during the useful life of the motor, it will be noted that a simple loosening of the nut 22 will suffice to loosen the mounting of the associated brushholder 12, after which the brushholder can be entirely removed for replacement, if necessary, or it can be readily adjusted radially, so as to raise or lower the brushholder-frame with respect to the surface of the commutator 6. A simple tightening of the nut 22 restores the brushholder-mounting to its normal operative condition. The nut 22 is provided with a locking washer 29, or other means intended to prevent the accidental loosening of the nut, but if the nut should become loosened in service, the motor does not lose its explosion-resistant qualities, because the head 24 on the stud 21 prevents the complete removal of the nut, the stud 21 cannot become disengaged from the inner clamping-block 16, and the flame-sealing clearance between the stud 21 and the holes 11 and 18 gives the motor an explosion-resistant characteristic, even when the nut 22 is loosened.

From the manufacturer's standpoint, it has already been noted that our invention is extremely desirable, both from the standpoint of its low cost, and from the standpoint of the accuracy which is practically obtainable.

While we have illustrated our invention in a single preferred form of embodiment, we wish it to be understood that our invention is not limited, in its broadest aspects, to all of the illustrated details. We desire, therefore, that the appended claims shall be accorded the broadest construction consistent with their language.

We claim as our invention:

1. A brushholder-mounting for an explosion-resistant motor, comprising, in combination: a motor-frame having a flat, accurately machined, brushholder-supporting surface at right angles to the motor-shaft, said frame having a plurality of axially extending holes through said machined

surface at various points around the frame; a plurality of underhung brushholders, each brushholder having two support-pins extending radially inwardly from an outer corner of the brushholder-frame; a plurality of pairs of outer and inner support-blocks, each pair having two sets of approximately semi-cylindrical seats for clampingly embracing the two support-pins of one of said brushholders; each of the outer support-blocks having a flat surface in engagement with the flat machined surface of the motor-frame, and having a hole between its two pin-engaging seats and acting as a continuation of one of the axially extending holes in the motor-frame, and being of a predetermined thickness for accurately spacing the two brushholder-pins from the accurately machined surface of said motor-frame; means for permanently retaining each of said outer support-blocks in its proper place against said machined surface; and a stud carried by each of said inner support-blocks and extending through the corresponding holes in the associated outer support-block and in the motor-frame, with a flame-sealing explosion-resistant clearance within said holes, each stud having a nut threaded on it, to engage the outer surface of the motor-frame, and having means on its outer end for preventing the complete removal of said nut after it has been turned back sufficiently to loosen the clamping-engagement of the associated brushholder.

2. A brushholder-mounting for a dynamo-electric machine, comprising, in combination: a machine-frame having an end-wall provided with a plurality of brushholder-supporting portions at various points around the frame, each of said brushholder-supporting portions including two spaced, radially extending, approximately semi-cylindrical seats in accurately predetermined positions, and each of said brushholder-supporting portions having an axially extending hole between its two seats; a plurality of underhung brushholders, each brushholder having two support-pins extending radially inwardly from an outer corner of the brushholder-frame in position to lie against the two seats of one of said brushholder-supporting portions; a supplementary clamping-block for completing each brushholder-mounting-means, each clamping-block having two spaced, approximately semi-cylindrical seats for engaging the two support-pins of its associated brushholder; and a stud carried by each of said supplementary clamping-blocks and extending through the corresponding hole in the associated brushholder-supporting portions of the machine-frame, with some freedom of a limited amount of axial movement in said hole, each stud having a nut threaded on it, to engage the outer surface of the motor-frame, and having means on its outer end for preventing the accidental removal of said nut after it has been turned back sufficiently to loosen the clamping-engagement of the associated brushholder.

3. The invention as defined in claim 1, characterized by each stud being threadedly carried by its associated support-block, and having a removable safety-device for locking it in place.

4. The invention as defined in claim 2, characterized by each stud being threadedly carried by its associated clamping-block, and having a removable safety-device for locking it in place.

JOHN E. PASTORET.
JOHN W. MORROW.
